ATTORNEY

UNITED STATES PATENT OFFICE.

GEORGE F. JACKSON, OF BYLLESBY, VIRGINIA.

GAS AND AIR MIXER.

1,382,363.

Specification of Letters Patent. Patented June 21, 1921.

Application filed June 17, 1918, Serial No. 240,557. Renewed April 7, 1921, Serial No. 459,308.

To all whom it may concern:

Be it known that I, GEORGE F. JACKSON, a citizen of the United States, residing at Byllesby, in the county of Carroll and State 5 of Virginia, have invented certain new and useful Improvements in Gas and Air Mixers, of which the following is a specification.

This invention relates to internal combustion engines, and more especially to charge-forming devices; and the object of the same is to produce an improved gas and air mixer whereby the charge after it passes the carburetor can be diluted with either cold air 15 or warm air or both, as the operator prefers.

A further object of the invention is to use the device for cooling the cylinders when coasting or running on little power.

Other objects are accomplished by this invention whose details will be set forth in the following specification, reference being made to the drawings, wherein:

Figure 1 is a side elevation of an automobile motor equipped with this invention.

Fig. 2 is a detail of one of the valves.

Fig. 3 is a plan view of the parts just in rear of the fan.

Fig. 4 is an enlarged sectional detail on the line 4-4 of Fig. 1.

Forward of the dash D of an automobile is located the engine whereof we are concerned only with the carburetor C, the inlet manifold M leading to the cylinders, the 35 exhaust manifold E leading therefrom, the water pipe W leading to the radiator R, and the fan F. All these parts may be of the usual or of any preferred construction, as my invention is applicable to engines of a 40 variety of makes with little modification if any. I will say at starting that it is possible that the carburetor C be fed with warm air through a pipe 1 leading from a box 2 standing adjacent the exhaust manifold E 45 as is now quite common, but the air so entering the carburetor is mixed with the vapor and forms part of the charge which flows through the manifold M to the cylinders in a manner well understood.

Coming now to the details of the present invention, in the fork of the manifold I insert a plug 3 having a jet orifice at its inner end, and to the outer end of the plug is connected a pipe 4 leading to a T-coupling 5

whose shank or stem is connected with said pipe and whose head is open at its extremes. Just in rear of the fan F I place a collector, here shown in the shape of an elbow 6, from which a pipe 7 leads to the rear, through a valve 8, and thence along another pipe 9 into the head of the T-coupling 5. Upon the rear portion of the exhaust manifold E a box 12 is held by a clip 18 or otherwise so that the air entering said box is heated, and a pipe 17 leads from this box through a valve 18, and thence through another pipe 19 into the other end of the head of the T-coupling 5. Each valve has a stem 16 provided with a crank 17 as best seen in Fig. 2, and pivoted to the cranks of the two valves are rods 20 and 21 leading rearward and upward through the dash D and having knobs or heads 22 on their rear ends, standing within reach of the operator.

Ordinarily both valves 8 and 18 will stand closed. The suction of the carburetor now draws air through the pipe 1, which air has already been warmed in the box 2, and the charge so formed is delivered through the manifold M to the cylinders as usual. When it is desired to dilute the charge after it leaves the carburetor, it can be done by admitting air which is either hot or cold. The air drawn in through the radiator by the fan F is blown into the collector 6 and along the pipe 7, and obviously when the valve 8 is opened, this air passes through the pipe 9 and coupling 5, down the pipe 4 and through the plug or nozzle 3 into the manifold at the point shown; and thereby the mixture within said manifold is diluted with cold air. On the other hand, if the valve 8 is closed and the valve 18 is opened, the suction within the manifold draws air from the box 12 which has already been heated by its proximity to the exhaust manifold E; and therefore the charge in the manifold is in this case diluted with air which is heated. Hence the operator is at liberty to dilute the charge with either cold or warm air, and in some cases both. I find that when the machine is coasting or running on very low power, it is quite possible to admit cold air which, while diluting the mixture serves to cool the cylinders. When an engine on the other hand is doing much labor, as for instance in ascending steep hills, I find it advisable to admit warm air to the manifold if,

indeed, the admission of warm air through the pipe 1 to the carbureter C, will not suffice. In either case the admission of air to the manifold after the charge has been formed will obviously dilute the charge so that an excessively rich mixture is not supplied to the engine, and therefore there is a proportionate saving of gasoline.

Whether the operator admits cold air or 10 warm air, or both, the use of the plug or nozzle 3 is serviceable because it produces a jet of the air admitted to the manifold, so that the air drawn into the same enters with great force and makes a perfect mix- 15 ture with the vapor therein.

The foregoing description and the drawings have reference to what may be considered the preferred, or approved form of my invention. It is to be understood that I 20 may make such changes in construction and arrangement and combination of parts, materials, dimensions, et cetera, as may prove expedient and fall within the scope of the appended claim.

Having thus fully described my invention,

what I claim as new and desire to secure by 25 Letters Patent, is:—

In an air feed for internal combustion engines, the combination with a jet nozzle directed into the inlet manifold and a feed coupling whose shank is connected with the outer end of said nozzle, a pipe line leading from one arm of the feed coupling, an L coupling threadedly mounted upon the free end of said pipe line, a fan delivering air into said line, said coupling being turned 35 so as to have its open end in the opposite direction from the rotation of said fan, a second pipe leading from the other arm of said coupling, a box adjacent the exhaust manifold and to which said second line is connected, independent valves in said line and manually operated means for controlling the valves.

In testimony whereof I affix my signature in presence of two witnesses.

GEORGE F. JACKSON.
